UNITED STATES PATENT OFFICE.

EDWARD CHESHIRE, OF MILWAUKEE, WISCONSIN.

TURBINE-BLADE.

SPECIFICATION forming part of Letters Patent No. 766,593, dated August 2, 1904.

Application filed October 1, 1903. Serial No. 175,316. (No model.)

To all whom it may concern:

Be it known that I, EDWARD CHESHIRE, a citizen of the United States, residing at Milwaukee, in the county of Milwaukee and State 5 of Wisconsin, have invented a certain new and useful Improvement in Turbine-Blades, of which the following is a full, clear, and exact description, reference being had to the accompanying drawings.

10 In the construction of turbines employing a large number of blades it is a great desideratum that such blades should be inexpensive of construction, efficient and economical in operation, and should be capable of attachment to and removable from their fixed or 15 moving parts in a simple and inexpensive manner.

My invention has in view the accomplishing of the above objects, and may be defined generally as consisting of the combination of 20 parts set forth in the claims hereto appended.

Referring to the drawings, Figures 1, 2, and 25 3 represent plan views of portions of rows of blades constructed in accordance with my invention. Figs. 4, 5, and 6 represent side elevations of such blades. Fig. 7 represents sectional details of a fixed and a movable member of a turbine, showing the manner of attaching the blades to such members.

30 Describing the parts by letters, the blades consist each of a blade portion proper, a , and a base portion a' . The blade portion, as shown, is convexo-concave and extends generally from one side of the base to the other, 35 projecting beyond the rear or discharge end thereof and terminating in a line with the side of the base. The angle of the blades may be varied in accordance with the special circumstances of each case and in itself forms no part 40 of my invention.

It will be observed that the bases are not rectangular, but that the faces thereof are inclined in the direction of the inclination of the blade, thereby permitting the blades to be 45 made of sufficient width to utilize the pressure fluid to the best advantage and at the same time reduce the overhanging or unsupported portions of the blades to a minimum.

The blades are supported on their runner 50 and fixed members A A' by means of grooves

a^2 cut in such members. These grooves are parallel with one another. In order to permit the blades to be readily and securely fitted in place and to be easily removed, I have constructed the bases of the blades and the grooves 55 as follows: Each side of the base is provided with a leg-like extension a^3 , projecting downwardly therefrom and in the plane of the side. From each side of the groove fitted for the reception of said base there extends an outwardly-inclined channel a^4 , corresponding in depth approximately to the length of each of said leg-like extensions. Between such channels a^4 there is a flat or plane portion a^5 , and between each pair of legs there is a corresponding flat or plane portion a^6 . The blades 60 are driven or otherwise forced into place in the grooves until further movement is stopped by the portions a^6 striking against the corresponding portions a^5 , the legs meanwhile 70 spreading into the downwardly-diverging channels provided for their reception, thereby locking the blades in position and forming a simple and secure connection for said blades with the fixed or running parts of the turbine. 75 These blades may be hot-pressed or drop-forged from steel or metal alloy having great tenacity and elasticity.

It will be observed, as shown in Fig. 7, that the depth of the groove to the stop portion a^5 80 is such relative to the depth of the bases of the blades to their corresponding stop portions a^6 that said bases project slightly above the surface of the fixed or running member 85 of the turbine in which they are inserted. The purpose of this construction will be apparent from an inspection of Fig. 7, wherein portions of rows of running blades are seen in operative relation to portions of rows of fixed blades. Owing to the necessity for providing sufficient clearance between the end of each blade and its opposite fixed or running member, some of the steam or other pressure fluid will escape through this clearance-space 90 without producing any effect upon the blade 95 unless means be provided for preventing such result. The projection of the bases beyond the surfaces of the runner and fixed members provides a continuous shallow pocket or channel between each pair of rows within or as 100

far as which the ends of the blades in the row carried by the opposite member project, thereby preventing loss of pressure fluid at the ends of the blades.

5. By the construction of blades and their co-acting parts herein set forth I have provided individual blades that are inexpensive in themselves, are readily inserted into or removed from their movable or fixed members without disturbing any other blade, and that are very effective in preventing losses of efficiency in the pressure fluid by reason of unnecessary clearance.
- Having described my invention, I claim—
15. 1. A blade for turbines consisting of a base portion and a blade portion, the lower discharge edge of the blade portion overlapping the rear or discharge end of the base portion, substantially as described.
20. 2. A blade for turbines consisting of a blade portion and a base portion, the blade portion extending from one side of said base portion to the other with its discharge edge overlapping the rear portion of said base portion, substantially as described.
25. 3. A blade for turbines consisting of a blade portion and a base portion, the base portion having side edges and front and rear faces and the blade portion extending from one side edge to the other with its discharge edge extending beyond the rear face of said base portion and in the plane of the corresponding side edge thereof, substantially as described.
30. 4. A blade for turbines consisting of a blade portion and a base portion having sides and front and rear faces, the lower discharge edge of the blade portion overlapping the rear face of the base portion and said faces being inclined toward the discharge edge of the blade, substantially as described.
35. 5. A blade for turbines consisting of a blade portion and a base portion, the base portion being thick with reference to the blade portion and provided with a pair of depending leg-like extensions adapted to be spread apart to lock the blade in place, substantially as described.
40. 6. A blade for turbines, consisting of a base portion and a blade portion, the base portion being thick with reference to the blade portion and provided at each side with a depending leg-like extension and a flat or plane portion intermediate of said extension, substantially as described.
45. 7. In a turbine, the combination of a series of blades each having a blade portion and a base portion, the discharge edge of the blade portion overlapping the rear or discharge end of its base portion and overhanging the front end of the base portion of the succeeding blade, substantially as described.
50. 8. In a turbine, the combination with a blade-carrying member having a groove therein, said groove having diverging channels, and a series of blades, each blade having leg-

like extensions driven into and spread apart by said diverging channels, substantially as described.

9. In a turbine, the combination of a series of blades, each consisting of a blade portion and a base portion, the base portion having parallel sides and parallel front and rear faces, the blade portion extending from one side of the base to the other and having its edges flush therewith and having its discharge edge overlapping the base of the succeeding blade, substantially as described.

10. In a turbine, the combination of a series of blades, each consisting of a blade portion and a base portion, the base portion having parallel sides and parallel front and rear faces, the blade portion extending from side to side of the base portion and having its edges flush therewith and its discharge edge overlapping the base of the succeeding blade, the faces of each base portion being inclined toward the discharge edge of the blade portion, substantially as described.

11. In a turbine, the combination with a blade-carrying member having a groove therein, said groove having an extension and a stop portion, of a series of blades, each having a base provided with an extension corresponding to the groove extension and a portion adapted to engage the stop portion of said groove, the distance of the stop portion of said groove from the surface of said member being less than the distance of the corresponding portion of the base from the upper surface of said base, whereby when the blades are fitted in the grooves a portion of the base of each blade projects above the surface of said member, substantially as described.

12. In a turbine, the combination of a blade-carrying member having a groove therein, said groove having diverging extensions, of a series of blades having each a base portion fitting in said groove, said base portion being provided with leg-like extensions driven into and spread apart by said groove extensions, substantially as described.

13. In a turbine, the combination of a blade-carrying member having a channel-shaped groove therein, said groove having diverging extensions from each lower angular portion thereof, of a series of blades having each a base portion fitting said groove and provided with leg-like extensions fitting in the groove extensions and spread apart thereby, substantially as described.

14. In a turbine, the combination of a blade-carrying member having a groove therein provided with extensions and a stop portion nearer the surface of said member than said extensions, of a series of blades having each a base portion fitting said groove, leg-like extensions interlocking with said groove extensions, and a stop portion engaging the stop portion in the groove, the depth of the base portion to its stop portion being greater than

the distance of the groove stop portion from the surface of the member, whereby a portion of the base projects beyond the surface of the member, substantially as described.

5 15. In a turbine, the combination of a blade-carrying member having a groove therein, said groove having a flat bottom and diverging extensions from each lower angular portion of said bottom, of a series of blades having each a base portion fitting in said groove, a pair of leg-like extensions driven into and spread by said groove extensions, and a flat portion intermediate of said leg-like extensions engaging the flat bottom of said groove, substantially as described.

10 16. In a turbine, the combination of a blade-carrying member having a groove therein, said groove having a flat bottom and diverging extensions from each lower angular por-

tion of said bottom, of a series of blades having each a base portion fitting in said groove, a pair of leg-like extensions driven into and spread by said groove extensions, and a flat portion intermediate of said leg-like extensions engaging the flat bottom of said groove, 25 the depth of the base portion of the blade to the portion intermediate of the leg-like extensions being greater than the distance from the surface of the member to the flat bottom of the groove, whereby a portion of the base 30 projects beyond the surface of the member, substantially as described.

In testimony whereof I hereunto affix my signature in the presence of two witnesses.

EDWARD CHESHIRE.
